(57) **CLAIM**

The ornamental design for a handle for a LED device as shown and described.

DESCRIPTION

FIG. 1 is a front elevational view of a handle for LED device;

FIG. 2 is a left side elevational view thereof;

FIG. 3 is a rear elevational view thereof;

FIG. 4 is a right side elevational view thereof;

FIG. 5 is a bottom plan view thereof;

FIG. 6 is a top plan view thereof; and,

FIG. 7 is a front perspective view thereof.

The broken line in the drawings depict portions of the handle for LED device that form no part of the claimed design.
